DELMER E. PRESTON AND WILLIAM H. ATKINSON, OF OMAHA, NEBRASKA,
ASSIGNORS OF ONE-FOURTH TO ALONZO N. BENN, OF OMAHA, NE-
BRASKA.

SCRAPER.

SPECIFICATION forming part of Letters Patent No. 695,231, dated March 11, 1902.

Application filed March 26, 1901. Serial No. 52,951. (No model.)

To all whom it may concern:

Be it known that we, DELMER E. PRESTON and WILLIAM H. ATKINSON, citizens of the United States, and residents of Omaha, in the county of Douglas and State of Nebraska, have invented a new and Improved Scraper, of which the following is a full, clear, and exact description.

The invention relates to scrapers used in pigs'-feet-cleaning and other machines; and its object is to provide a new and improved scraper more especially designed for effectively and quickly cleaning pigs' feet, pigs' heads, and like articles and without requiring subsequent trimming with a knife and without danger of cutting the article, the scraper being simple and durable in construction and not liable to wear out in a short time, as is the case with wire brushes heretofore constructed and used for the purpose mentioned.

The invention consists of novel features and parts and combinations of the same, as will be fully described hereinafter and then pointed out in the claims.

25 A practical embodiment of the invention is represented in the accompanying drawings, forming a part of this specification, in which similar characters of reference indicate corresponding parts in all the views.

30 Figure 1 is a reduced side elevation of the improvement with parts in section. Fig. 2 is a sectional plan view of the same on the line 2 2 in Fig. 1. Fig. 3 is a side elevation of the improvement with a head removed and parts shown in section. Fig. 4 is a transverse section of one of the scraper disks and blades, the section being on the line 4 4 in Fig. 3. Fig. 5 is a perspective view of one of the cushion-blocks. Fig. 6 is a face view of one of the 35 blades for cleaning a pig's foot between the toes, and Fig. 7 is an edge view of the same.

The improved scraper is in the form of a wheel adapted to be rotated by suitable means and preferably forming part of a pigs'-feet-cleaning or other similar machine, the arrangement being such that the article to be cleaned is moved lengthwise under the wheel by suitable feeding devices, or it may be held and moved under the wheel by an operator.

40 As shown in Figs. 1, 2, and 3, the wheel is

secured on a shaft A and is provided with a plurality of disks B B' B², on which are mounted scraper-blades C C' C², respectively, each blade having its inner end formed into a pivot C³, set in a correspondingly-shaped recess in 55 the face of the corresponding disk to allow the blade to swing. The shank C⁴ of each blade extends radially in an outward direction from the pivot C³, and the front end of said shank abuts against a shoulder B⁵, forming an integral part of the corresponding disk B, B', or B². The shank C⁴ of each blade is pressed on the opposite side or back by a cushion-block D, of rubber or other suitable elastic material, and set with said shank in a 60 recess B⁴, formed in the face of the corresponding disk B, B', or B².

65 Each block D is preferably provided at its inner end with an offset or foot D' for holding the block against outward movement in 70 the disk when the wheel is rotated, thus requiring no further particular fastening means to hold the block in position on a disk.

75 The outer ends of the scraper-blades C C' are arranged in their respective disks B B' so as to have a staggering relation to each other and are slightly curved in the direction of their length and of such width as to overlie each other in the path in which they travel when the wheel is revolved, as will be readily 80 understood by reference to Fig. 2. The disk B² is spaced from the disk B' by suitable washers E, and the outer ends of the blade C² are narrow to readily enter between the toes of a pig's foot, and thereby properly clean the foot 85 between the toes, it being understood that the other blades C C' serve to more particularly clean the outer surface of the article.

90 In order to hold the several disks B B' B² in position, suitable heads F F' or other devices are employed for the purpose.

95 It is understood that the head F engages the front face of the disk B and also the front faces of the shanks C⁴ and the pivots C³, while the back of the disk B engages the front face of the next following disk B' and its blade C'. One of the washers E forms a front for the disk B², so that the scraper-blades C C' C² are not liable to become disengaged from their corresponding disks.

- When the device is in use and the wheel is rotated, then the cutting edges of the scraper-blades cut off any surplus material from the pigs' feet or other articles under treatment, it being understood that when a scraper-blade strikes an obstruction or hard matter on the article then it readily yields in a backward direction against the tension of the corresponding cushion-block D, so that the obstruction is passed without cutting into the flesh of the article. When the wheel is in use, it rotates in the direction of the arrow a'. (See Figs. 1 and 3.)
- Having thus fully described our invention, we claim as new and desire to secure by Letters Patent—
1. In a scraper, a revoluble disk provided upon its circumference with a series of recesses, each of which comprises an undercut portion to afford anchorage, a blade inserted in each of said recesses, and a block provided with a tongue entering said undercut portion, said block being fitted into said recess against said blade.
  2. A scraper, comprising disks provided with blades yieldingly mounted thereon, said blades being provided with widened operating edges, contiguous disks being so disposed that the blades of one disk alternate with the blades of another disk.
  3. A scraper, comprising disks provided with blades yieldingly mounted thereon, said blades being provided with widened operating edges, contiguous disks being so disposed that the operating edges of one disk project partially into the path of the operating edges of an adjacent disk, for the purpose of insuring action upon every part of the surface to be scraped.
  4. A scraper, comprising a revoluble disk provided with recesses in its edge and also in one of its faces, a blade provided with an enlarged head anchored in one of said recesses and extending radially outward from said disk, and a block mounted in the other of said recesses, for holding said blade.

5. A scraper, comprising a revoluble disk provided in one of its faces with cylindrical recesses and in its edge with L-shaped recesses, blades provided with pivotal heads for engaging said cylindrical recesses, and L-shaped blocks fitting said L-shaped recesses and engaging said blades.

6. A scraper, comprising a revoluble disk provided with outer recesses in its edge and also with inner recesses in one of its faces, said recesses communicating with each other, blades provided with pivotal heads entering said inner recesses and projecting radially through said outer recesses, and compressible members located in said outer recesses and pressing upon said blades for the purpose of rendering said blades yieldable.

7. In a scraper, a revoluble disk provided with recesses, from each of which extend undercut portions, a scraping-tool provided with an enlargement forming a pivotal connection in one of said undercut portions, and a resilient member located in said recess and engaging the other undercut portion, and yieldingly pressing against said scraping-tool, substantially as described.

8. A scraper, comprising a revoluble disk, provided with a plurality of recesses, from each of which extends a plurality of undercut portions, a scraping-tool inserted in each recess and provided with an integral part which forms a direct pivotal connection with one of said undercut portions, and a compressible member located in said recess and engaging the other undercut portion and resting against said scraping-tool, substantially as described.

In testimony whereof we have signed our names to this specification in the presence of two subscribing witnesses.

DELMER E. PRESTON.
WILLIAM H. ATKINSON.
